George E. Hermick
ATTORNEY

UNITED STATES PATENT OFFICE.

STANISLOVAS MOLIS, OF RACINE, WISCONSIN.

FOLDABLE BED-SPRING.

1,370,036.

Specification of Letters Patent.

Patented Mar. 1, 1921.

Application filed June 15, 1920. Serial No. 389,114.

To all whom it may concern:

Be it known that I, STANISLOVAS MOLIS, a citizen of Lithuania, residing at Racine, county of Racine, and State of Wisconsin, 5 have invented certain new and useful Improvements in Foldable Bed-Springs, of which the following is a specification.

My invention relates to certain improvements in bed-springs, particularly foldable 10 or sectional bed-springs, and the object thereof is to provide a bed-spring, the single parts of which can be easily detached from each other, the construction and arrangement being such that the bed-spring may 15 be contracted into about one-third of the space occupied thereby when in use.

A further object of the invention is to provide a sectional bed-spring, which can be easily handled and lifted out and into a bed- 20 stead by a single person without inconvenience.

The invention is fully disclosed in the following specification, of which the accompanying drawing forms a part in which—

25 Figure 1 is a plan view of my improved bed-spring.

Fig. 2 is a side view thereof, and

Fig. 3 is a side view of the bed-spring in position in a bed-stead.

30 Referring to the figures of the drawing, like numerals of reference designate similar parts in the several views.

The bed-spring 10 is composed of three parts 11, 12 and 13, each of which comprises 35 two longitudinal side bars 14 connected by a plurality, for instance as shown, three strong, straight wires 15, while the free ends of a pair of bars 14 are connected by strong zig-zag wires 16.

40 A plurality of strong, straight wires 17 for instance, as shown four, are uniformly spaced from each other and rectangularly disposed to the wires 15 and connect the wires 16 of each section.

45 At the points of intersection between the wires 15 and 17 coiled or spiral springs 18 which are supported by the usual slats are arranged, as is customary with bed-springs.

Each of the sections 11, 12 and 13 is provided 50 at the inner ends of their respective bars 14 with a socket 19 for the reception of

a pin 20 of a connecting link 21, the other pin of which is adapted to engage the socket 19 of the next adjoining section.

It will be clear that the central section 12 55 must be provided with sockets 19 at the inner as well as the outer end of its bars 14.

From the foregoing description it will be clear that a bed-spring 10 constructed according to my invention can easily be placed 60 into a bed-stead 22 by a single person without inconvenience, by first placing section 11 into the bed-stead frame so that the ends of its bars 14 which are connected by springs 16 rest upon the foot part of the frame. 65

Hereafter the next section 12 is placed into the bed to engage the section 11 and the pins 20 of the links 21 are introduced into the respective sockets 19 to combine both sections, hereafter the section 13 is placed 70 into the bed-stead and connected to section 12 in a similar manner.

It is evident that the bed-spring will readily yield pressure from any direction, and therefore be very comfortable to an 75 occupant, and will receive a mattress and support it perfectly. The links, though shown as rectangular may be U-shaped or of other forms.

The complete device is simple and cheaply 80 and easily constructed.

What I claim and desire to secure by Letters Patent of the United States is as follows—

A bed-spring composed of three sections, 85 each comprising a pair of frame bars provided with sockets, a pair of zig-zag wire springs connecting the corresponding free ends of said bars, a plurality of rectangularly intersecting strong straight wire 90 springs connected with their ends to said bars and said zig-zag wires respectively, coiled wire springs at the points of intersection between each two of said sets of strong straight wire springs and links each provided with two pins for engaging with one pin the socket of one and with the other the socket of the next adjoining section for connecting two of said sections. 95

In testimony whereof I have affixed my 100 signature.

STANISLOVAS MOLIS.
